UNITED STATES PATENT OFFICE.

FRANK E. FERNALD, OF MILTON, NEW HAMPSHIRE, ASSIGNOR TO UNITED SHOE MACHINERY COMPANY, OF PATERSON, NEW JERSEY, A CORPORATION OF NEW JERSEY.

APPARATUS FOR USE IN THE MANUFACTURE OF BOOTS AND SHOES.

1,094,546.

Specification of Letters Patent. Patented Apr. 28, 1914.

Application filed October 20, 1911. Serial No. 655,697.

To all whom it may concern:

Be it known that I, FRANK E. FERNALD, a citizen of the United States, residing at Milton, county of Strafford, State of New Hampshire, have invented certain Improvements in Apparatus for Use in the Manufacture of Boots and Shoes, of which the following description, in connection with the accompanying drawings, is a specification, like reference characters on the drawings indicating like parts in the several figures.

This invention relates to an apparatus for use in the manufacture of boots and shoes.

More particularly it relates to an apparatus for use in lasting boots and shoes.

The operation of lasting the toe portions of shoes results in damaging a considerable percentage of shoes by causing the leather to crack or break where it is pulled tightly over the bottom of the last. This result is due largely to the fact that a great deal of upper material, including portions of the cap, lining and the toe box or toe stiffener, is gathered at this point, and the wipers of the lasting machine must necessarily pull the leather very tightly in order to overcome its tendency to pucker and crimp. While it has usually been customary to last the shoe with the leather in a moistened or "tempered" condition, this expedient does not avoid the damage referred to, but, in many cases, merely delays the cracking or breaking of the leather since this action occurs later while the shoe is drying out. While the cracking of the leather at the tips causes more or less trouble in substantially all styles of shoes, it is especially likely to occur in those shoes having high toes in which, of course, the amount of upper material that must be disposed smoothly about the toe is increased and, consequently, the strains placed upon the stock during the lasting operation are correspondingly increased.

I have found that the percentage of damaged shoes may be greatly reduced by treating the toe portion of the shoe with steam or hot vapor just before the lasting operation is performed on this part of the shoe. The vapor penetrates the leather and other parts of the upper, rendering them so soft and pliable that they may be worked over the toe much more easily and smoothly than when treated according to the usual process.

The present invention provides an appa-

ratus which is adapted particularly for 55 treating the toes of shoes in the manner above described, although it is considered within the scope of this invention to treat other parts of a shoe in the same manner.

One embodiment of the invention is illustrated in the figure of the accompanying drawing.

The apparatus shown comprises a tank 2, which may conveniently be made of sheet metal or of any other suitable material. A 65 steam pipe 4 is led through the tank and is provided with a valve 6 on the live steam side and a valve 8 on the exhaust side. This pipe has perforations 10 along its lower side to allow steam to escape into the tank. An 70 outlet or drip pipe 12 is set into the bottom of the tank to draw off any surplus water, a valve 14 being provided to enable the workman to regulate the quantity of water within the tank. I prefer to run the apparatus with the steam pipe submerged, the valve 8 closed, and the valve 14 adjusted to allow the water to escape just fast enough to keep substantially a constant level in the tank. Any surplus water may be drawn off 80 through the valve 8 or the valve 14. This arrangement prevents the escape of live steam into the tank which might burn or otherwise injure the shoe. Furthermore, it enables the workman to regulate the temperature of the water by adjusting the valve 6.

In the front wall of the tank an aperture 16 is provided for the reception of the toe portion of one or more shoes. The shoe is 90 protected from contact with the metal of the tank by pieces, 18 and 20, of wood or other heat insulating material placed, one on the inside and the other on the outside of the tank, and secured together and to the tank 95 by screws 22. These members project above the edge of the metal wall and are shaped to conform to the part of the shoe which rests upon them.

In order to support the shoe in the apparatus, there is provided a rest or frame 24, consisting of a support carrying two pairs of pins 26 that project upwardly and away from the front wall of the apparatus just below the aperture 16. This rest may be 105 secured to the tank or it may be merely placed in front of the tank on the bench upon which the tank rests.

The apparatus shown in the drawings is provided with a tray positioned within the tank at a point below the space occupied by the shoe. This tray supports a layer of fibrous material 30, such, for instance, as felt or cotton waste. Steam or vapor escapes through the numerous perforations, as 32, in the tray and through the material 30 into contact with the shoe. An exhaust pipe 34 set into the top of the tank conducts the vapor away from the apparatus. The material 30 retards the flow of vapor through the tank and cools the vapor somewhat. It is of value more particularly in those cases in which the workman wishes to use steam coming directly from the pipe 4 without first escaping into water, as in the preferred arrangement.

In using the apparatus, the workman usually lasts the sides and heel of a shoe and then places it in the rest 24 with its toe projecting into the tank where it will be subjected to the action of the vapors rising from the body of water. The workman next lasts the sides and heel of another shoe and places it in the rest with its toe in position to be steamed. By this time the first shoe has become sufficiently softened to last easily and the workman therefore removes it and lasts the toe while the leather is still hot and moist. I have found that the treatment of the stock in this manner makes the lasting of the toes very much easier, thus enabling a workman to last more shoes in a given time; that it avoids most of the damage that heretofore has been experienced in lasting toes, and that the shoes dry out in a better condition than when treated in accordance with the methods heretofore practised.

Obviously it may be advantageous under some conditions to treat the toes of shoes in this manner before the pulling over operation, or to treat some portion of the shoe other than the toe, and I regard such operations as coming within the scope of the present invention.

Having thus described my invention what I claim as new and desire to secure by Letters Patent of the United States is:

1. An apparatus of the character described comprising a tank for a body of water, means for heating the water and means for supporting a shoe with its toe portion only in position to be acted upon by the vapor arising from said body of water.

2. An apparatus of the character described comprising a tank for a body of water, means for supporting a shoe with its toe in said tank above the surface of the water and a steam inlet pipe arranged to deliver steam into the water.

3. An apparatus of the character described comprising a tank adapted to hold a body of water, said tank having an aper-

ture for the reception of the toe portion of a shoe, means to deliver steam into the lower part of said tank, an outlet from said tank and means whereby the quantity of water in the tank may be regulated by the workman. 70

4. An apparatus of the character described comprising a tank having an opening in one of its walls for the insertion of the toe portion of a shoe, a supporting frame for the shoe positioned in front of said opening, said frame being open at its front end to permit the shoe to be inserted into and withdrawn from the opening in the tank in substantially a straight line and means for supplying vapor to the tank. 75

5. An apparatus of the character described comprising a metal tank having an aperture for the reception of the toe portion of a shoe, a rest positioned in front of the aperture to support a shoe with its toe in said aperture, means for protecting the shoe from contact with the metal of the tank and means for supplying vapor to the tank. 80

6. An apparatus of the character described comprising a tank having an aperture for the reception of a portion of a shoe, a rest positioned adjacent to said aperture to support a shoe with its toe portion in said aperture and means for supplying vapor to said tank. 90

7. An apparatus of the character described comprising a tank having an aperture for the reception of a portion of a shoe, a rest positioned in front of said aperture to support a shoe with its toe in said aperture, a support in the tank below the position occupied by the toe of the shoe for fibrous material and means for generating vapor in the tank below said fibrous material. 100

8. In an apparatus of the character described, in combination, a metal box provided with an opening in one face for the insertion of the toe portion of a shoe, a rest for the shoe arranged with relation to the said opening to support the toe piece out of contact with the opening in the box, and means for supplying said box with vapor. 105

9. In an apparatus of the character described, in combination, a box provided with an opening in one of its vertical faces for the insertion of the toe portion of a shoe, a supporting frame for the shoe secured to said box in front of said opening and open at its front end to permit the shoe to be inserted into and withdrawn from the opening in the box in a substantially straight path, and means for supplying said box with vapor. 115

10. In an apparatus of the character described, in combination, a box provided with an opening in one of its vertical faces for the insertion of the toe portion of a shoe, a partition wall in said box below said opening forming chambers in communication 125

with each other, and a steam inlet pipe extended through the lower part of said box and provided within the box with an inlet port for said lower chamber.

5. 11. An apparatus of the character described comprising a tank having one or more apertures for the reception of the toe of a shoe, means for supporting a shoe with its toe in the tank, means for supplying hot

vapor within the tank, and protecting means 10 for the shoe.

In testimony whereof I have signed my name to this specification in the presence of two subscribing witnesses.
